ROTARY SEAT ATTACHMENT FOR
BARBER CHAIRS

David M. Powell, La Junta, Colo.

Application December 18, 1944, Serial No. 568,678

5 Claims. (Cl. 155—81)

1

This invention relates to chairs and has relation more particularly to a chair of a type used by barbers, beauticians or the like and it is primarily an object of the invention to provide an attachment for the chair whereby the operator may be seated while working.

The invention also has for an object to provide a seat structure for use with a barber chair or the like which includes a support directly engaged with the supporting base of the chair together with a seat mounted upon the support in a manner to be readily and conveniently moved toward or from the chair and wherein the mounting for the support is such as to allow the same to be readily shifted or adjusted to any desired selected position around the chair.

The invention consists in the details of construction and in the combination and arrangement of the several parts of my improved chair whereby certain important advantages are attained and the article rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in section and partly in elevation illustrating a chair structure in accordance with an embodiment of the invention, the main chair being diagrammatically illustrated;

Figure 2 is a transverse sectional view taken through the lower portion of Figure 1;

Figure 3 is a detail sectional view taken substantially on the line 3—3 of Figure 1;

Figure 4 is a detail sectional view illustrating the post holding means, certain of the parts being in plan;

Figure 5 is a fragmentary sectional view illustrating another embodiment of the invention.

As illustrated in Figures 1 to 4 B denotes a base for a chair of a type generally used by barbers, beauticians and the like and which includes the usual upstanding central column 1 and the bottom floor engaging surrounding flange 2. Closely surrounding the column 1 is a sleeve 3 of desired dimensions and which has its lower end contacting from above an annular cushion 4 of rubber or other desired material and which cushion is interposed between the sleeve 3 and the flange 2. Threading through the opposite end portions

of the sleeve 3 are the screws 5 which coact with the column 1 to properly center and hold the sleeve 3 in position with respect to the column. The inner ends of the screws 5 carry the yielding pads 6 which have direct contact with the surface of the column 1 and serve to protect such surface against marring.

The lower end portion of the sleeve 3 has integrally formed therewith an outstanding 10 rounding flange 7 having an upwardly facing substantially flat face a at right angles to the axial center of the sleeve 3. This face a has provided therein a continuous raceway 8 concentric to the sleeve 3. An annular member M closely 15 surrounds the sleeve 3 and is supported by the flange 7. The under face of this member M is provided therearound with a raceway 9 concentric to the axis of the member M and which overlies the raceway 8 when the member M is in applied 20 position. Interposed between the applied member M and the flange 7 are the ball bearings 10 which ride within the raceways 8 and 9.

The member M is held in position upon the sleeve 3 by a collar 11 threading upon the sleeve 3 above the applied member M. The opposed 25 faces of the member M and the collar 11 are provided with the continuous raceways 12 for the ball bearings 13 interposed between the member M and the collar 11.

After the proper application of the member M around the sleeve 3, a dust guard or ring 14 is secured around the column 1 above the applied sleeve 3, said guard or shield being of such dimensions and design to overlie the upper portion of the sleeve 3 and extending in relatively close proximity to the applied collar 11.

The member M is provided with an outwardly and radially disposed arm or block 15 having an opening therethrough in its central part. In communication with this opening 16 is a second opening 17 substantially at right angles thereto and which opens at the edge face of the arm or block 15. This opening 16 is of a stepped type to provide the internal and outwardly facing shoulder 18.

Insertable from above through the opening 16 and snugly fitting therein is a post 19 preferably tubular. This post 19 is of desired length and has its upward end continued by a laterally inclined extension post 20. The upper or outer end portion of the extension post 20 is continued by the outwardly directed parallel spaced tracks 21 substantially in right angular relation with respect to the post 19 or more particularly the top and bottom edge faces b and c thereof. The tracks 21 are in relatively close proximity to

each other and freely positioned therebetween is an elongated carriage block 22 of such dimensions as to extend above and below the tracks 21. The carriage block 22 fore and aft thereof and above the tracks 21 is provided at opposite sides with the grooved wheels 23 which ride upon the top edge faces b of the tracks 21.

The carriage block 22 below the tracks 21 at opposite sides thereof and substantially midway of the fore and aft wheels 23 is provided with the grooved wheels 24 which contact with the bottom edge faces c of the tracks 21.

The carriage block 22 substantially midway of its ends is provided with an opening 25 through which extends from above a seat post 26. In 15 swivel connection, as at 27, with the upper end portion of the post 26, is a seat 28.

Insertable within the opening 17 of the arm or block 15 from without, is a lock pin 29 which normally engages one of the holes or notches 30 in the post 19 and spaced lengthwise thereof. The coaction of this pin 29 with the post 19 locks the post 19 in selected vertical adjustment within the limitations afforded by the holes or notches 30.

The lock pin 29 outwardly of the shoulder 18 of the opening 17 is provided with an outwardly disposed surrounding flange 31 against which presses a coil spring 32 surrounding the pin 29. This spring 32 also bears against a bushing 33 threading into the outer portion of the opening 17. This bushing 33 also provides means for regulating the tension of the spring 32 and to facilitate the desired rotation of the bushing 33 the outer end portion thereof carries an operating head 34 which at all times is positioned outwardly of the opening 17. The outer portion of the pin 29 freely passes through the bushing 33 and coupled, as by threading, to the outer end portion of this pin 29 and outwardly of the bushing 33, is a pull button 35 whereby the pin 29 may be conveniently moved outwardly into release position with respect to the post 19.

The seat post 26 is also provided therealong with the spaced holes or notches 36 with which selectively engages a locking pin 37 slidably disposed within the properly positioned opening 38 communicating with the opening 25. This pin 37 is mounted and operated in substantially the same manner as the pin 29 hereinbefore referred to.

It is believed to be obvious from the foregoing that a chair embodying the present invention provides means whereby a barber, beautician or kindred operator may be seated when working and it is also believed to be apparent that the operator while seated can effectively work due to the ready rotation of the member M around the column 1 or more particularly to the applied sleeve 3 and also on account of the ready travel of the seat 28 along the tracks 2 toward or from the chair.

In the embodiment of the invention as illustrated in Figure 5, the column 39 of the chair base C is provided therearound at its lower part with an outstanding integral flange 40 upon which rests from above a surrounding annular member A which is held in working position by a collar 41 threading upon the column 39 and coacting from above with the member A.

This annular member A has operatively engaged therewith the post 42 comprised in the operator seat structure which will be similar to that hereinbefore described in connection with the first embodiment of the invention.

It is believed to be obvious that the first embodiment of the invention is one wherein the operator or auxiliary seat structure can be readily applied to a chair base previously in use whereas the second embodiment of the invention particularly embodies a type of base for a new barber chair or the like.

From the foregoing description it is believed to be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with the base for a barber chair or the like including an upstanding column, a member supported for turning movement around the column, a seat post carried by and extending upwardly from said turning member, outstanding spaced tracks carried by the upper portion of the post and arranged side by side, 20 a carriage block freely positioned between the tracks and extending above and below the tracks, parts carried by the block at opposite sides thereof and fore and aft of the block riding on the tracks from above, parts carried by the block at opposite sides thereof for engaging the tracks from below, and a seat carried by the block.

2. An attachment for a chair having a vertical cylindrical base portion, comprising means encircling said cylindrical base portion providing vertically spaced bearing guides, an annulus encircling said base portion between said guides for turning around the base, said annulus having a radial, outwardly directed extension, the extension having a vertical bearing opening there-through, a post extending through and secured in said opening, the post having an upper portion directed radially outwardly with respect to the cylindrical base portion, said upper portion being divided into two spaced parallel parts providing tracks, a body between said tracks, rotary bearing members carried upon opposite sides of said body and engaging said tracks to support the body for free movement longitudinally of the tracks, and a seat supported on the body.

3. An attachment for a chair, as set forth in claim 2, in which said rotary bearing members comprise a pair of wheels rotatably mounted upon the body at each side and adapted to engage and turn on the top of the adjacent track, and a single wheel rotatably mounted upon each side of the body in a vertical plane passing centrally between the adjacent pair of wheels, and adapted to engage and turn on the lower side of the adjacent track.

4. An attachment for a chair having a vertical cylindrical base portion merging with an outwardly flaring circular part adapted to rest upon a supporting surface, comprising a sleeve having said cylindrical base portion extending therethrough, the sleeve being supported from its lower edge upon the outwardly flaring lower part of the base portion, threaded members passing through said sleeve and engaging the cylindrical base portion and designed to secure the sleeve against movement with respect to such cylindrical portion and concentric therewith, said sleeve having an integral outwardly directed encircling flange and having screw threads formed externally therearound above said flange, a ring encircling the sleeve and threadably engaged with said

screw threads, said ring and flange having spaced relation and forming bearing elements, an annulus encircling the sleeve and rotatably maintained between the bearing elements, said annulus having a radial, outwardly directed extension, the extension having a vertical bearing opening therethrough, a post having a vertical portion secured in said bearing opening and a horizontal portion extending radially outwardly with respect to a cylindrical base portion, and a seat supported upon the outwardly directed portion of the post.

5. An attachment for a chair, as stated in claim 4, with a cushioning means interposed between the lower edge of said sleeve and the flaring part of said base, upon which the sleeve is supported.

DAVID M. POWELL.
